UNITED STATES PATENT OFFICE.

SAMUEL GABRIEL, OF NEW YORK, N. Y.

ENVELOPE.

SPECIFICATION forming part of Letters Patent No. 534,824, dated February 26, 1895.

Application filed January 14, 1895. Serial No. 534,802. (No specimens.)

To all whom it may concern:

Be it known that I, SAMUEL GABRIEL, a citizen of the United States, residing in the city, county, and State of New York, have invented 5 certain new and useful Improvements in Envelopes, of which the following is a specification.

This invention relates to an improved envelope for inclosing and storing various paper 10 articles, said envelope being made of paper, pasteboard, or other suitable material, so as to represent a trunk, basket, or other suitable article; and the invention consists of an envelope formed of paper or other suitable material, provided with an upper and a lower 15 flap folded in parallel lines with the body, the upper flap being made of rhombic shape and the body having at two diagonally opposite corners suitable inclinations, while the lower 20 flap is provided with a downwardly-extending wing at one side, the outer and inner surfaces of the upper flap representing the lid of a trunk, basket, or other suitable article, while the outer surface of the lower flap represents 25 the body of a trunk, or the like, as will be fully described hereinafter and finally pointed out in the claims.

In the accompanying drawings, Figure 1 represents a front-elevation of my improved 30 envelope. Fig. 2 is a vertical transverse section of the same on line 2, 2, Fig. 1. Fig. 3 is a front-view of the envelope, shown with the top-flap in open position. Fig. 4 is a vertical transverse section on line 4, 4, Fig. 3. Fig. 5 is a front-view of the blank from which the envelope is made. Fig. 6 is a vertical transverse section of the same on line 6, 6, Fig. 5, and Fig. 7 is a rear elevation of the blank from which my improved envelope is made. 35

40 Similar letters of reference indicate corresponding parts.

Referring to the drawings, A represents the body or main portion of the blank from which the envelope is made. The body A is cut off 45 at the two diagonally-opposite corners α , α' , and made in one integral piece with a lower flap B and an upper flap C, the former being of less width than the body A and provided at its right hand side with a wing B', the 50 edges of which extend downwardly and are made at the same inclination as the lower corner α' of the body A to the base of the

same. The upper flap is made of rhombic shape and of such width that when the same is folded down on the upper part of the body 55 A, it closes the part left uncovered by the lower or bottom flap, as shown in Fig. 1. The lower flap B, B', is attached to the body A by being pasted or otherwise fastened to its opposite, (parallel,) edges, the upper flap being 60 also fastened in any manner to the lower flap or to the body A, so that any suitable articles of flat shape which are desired to be placed in the envelope can be retained in the same. The exterior and interior surface of the upper flap C is printed in colors in the design of 65 the lid of a trunk, while the lower flap B, B', is finished in the perspective shape of the body of a trunk, the main body being also provided at its upper left-hand corner with a 70 suitable imitation of the interior of a trunk, so that the envelope has the appearance of a trunk in which articles are placed.

It is obvious that in place of a trunk a wicker basket, or any similar article, may be 75 represented, in which case the bottom and top-flaps are reproduced in the perspective of the top and front of the article that is desired to be represented.

My improved envelope is adapted for different purposes, and forms an attractive envelope for holding paper dolls and other toys for children's use.

Having thus described my invention, I claim as new and desire to secure by Letters 85 Patent—

1. An envelope, composed of a main-body cut off at two diagonally-opposite corners, a lower flap provided with a wing at the side adjacent to the lower cut off corner of the 90 body portion, the upper and lower edges of the wing being made at the same inclination as the cut off corner, and an upper flap having its side edges at an inclination corresponding to the upper cut off corner of the 95 main body, said lower and upper flaps being made integral with the main-body and finished in such a manner as to represent a suitable article, substantially as set forth.

2. An envelope, consisting of one integral 100 blank, composed of a main-body having two of its diagonally-opposite corners cut off, a lower flap extending along the base of the main-body and provided with a downwardly-

inclined wing adjacent to the lower cut off corner and forming the same angle of inclination with the base of the main-body and an upper flap extending from the upper edge of
5 the main-body at the same angle of inclination as the cut off upper corner, the outer surface of the lower flap representing a perspective of the body of a trunk, basket, or other article, while the front and rear surfaces of
10 the upper flap represent the inner and outer perspectives of the lid of a trunk or other

article, so that when the flaps are folded over the main-portion the representation of a trunk, basket or other article is obtained, substantially as set forth.

15

In testimony that I claim the foregoing as my invention I have signed my name in presence of two subscribing witnesses.

SAMUEL GABRIEL.
